[57] ABSTRACT

The present disclosure is directed to a lighter - ship stabilizing system for securing vertical stacks of lighters within cargo holds against tilting or rocking of the stack of lighters relative to the ship to effectively make the stack of lighters and the ship a single instrumentality which resists relative motion between lighters and ship incident to dynamical sea conditions such as pitch, roll and yaw. This rigid interplay between lighter and ship is based upon the fact that the lighters may be nested or stacked within the hold so that as between lighters in a particular stack there is interlocking rigidity and the stack is made rigid with the ships hull by wedging the stacks of lighters against the hull. This interlocking is attained by the use of wedge blocks secured to the hull and tapered wedges which are dropped between the stack of lighters at each lighter and rigid part of the ships hull.

ATTORNEY,

LIGHTER - SHIP STABILIZING SYSTEM

An object of the present invention is the quick rigid securing of lighters stacked in cargo holds of a ship relative to the ship so as to eliminate relative motion between the lighters and ship incident to dynamical forces to which the ship is subjected when underway.

A further object of the present invention is the provision of a mechanically simple locking means having few moving parts and being extremely easy to actuate and which gives a rigid four point fix between the lighter and hull.

With the foregoing and other objects in view, the invention will be more fully described hereinafter, and will be more particularly pointed out in the claims appended hereto.

In the drawings, wherein like symbols refer to like or corresponding parts throughout the several views:

FIG. 1 is a fragmentary transverse sectional view through a lighter carrying cargo ship showing the stacked lighters wedged in place against walkways.

FIG. 2 is a fragmentary top plan view of a lighter hold section showing the lighters wedged in place.

FIG. 3 is a fragmentary transverse section taken at an enlarged scale through a lighter - wedge and wedge plate connection with parts broken away and parts shown in section.

FIG. 4 is a perspective view of the lighter stabilizing wedge and wedge guide and bearing block employed with the present invention.

Referring now to FIG. 1, 10 designates generally a cargo ship having a hold 11 in which are vertically stacked lighters 12 resting upon nesting columns 13. Outwardly of the lighter holds 11 are wing tanks 14 for controlling trim and buoyancy of the ship.

Between the end walls 12A of the stacked lighters 12 and the bulkhead 15 of the lighter hold 11 there are walkways 16 running longitudinally of the ship and having upstanding hand rails 17. There are walkways 16 at each lighter deck level. Secured to the free end of the walkways 16 are wedge guide and bearing blocks 18,

and as best shown in FIG. 4 the block 18 is tapered from top to bottom and has a tapered slot 19 in its front face. A stabilizing wedge 20 has a flat face 21 and a tapered face 22. As shown in FIG. 3, when the lighters 5 are stacked in the hold, one upon another with the major axis of the lighter at a right angle to the major axis of the ship, the wedge 20 is inserted into the slot 19 of the block 18 in such a manner that the flat side 21 of the wedge 20 bears against the lighter end wall 12A and the tapered side 22 is complementary to the tapered slot 19 in block 18, the wedge 20 thereby becoming captive by slot 19 against movement across the end wall 12A of lighters 12 in one direction and by wedging action and gravity in the other direction.

15 15 Above the main deck 23 of the ship 10 and extending about the cargo or lighter hold opening is a coaming 24 upon which is received a hatch cover 25. This cover 25 acts as a base upon which are stacked one or two additional lighters 12.

20 20 Each wedge 20 is rendered captive to its general area of use by a length of chain 26 one end of which is secured to the ship and the other end of which is secured to the wedge.

What I claim is:

25 25 1. In combination with a ship having cargo holds in which lighters are vertically stacked with the major axis of the lighter at right angles to the major axis of the ship and in which walkways are mounted vertically one above another on the transverse bulkhead of the cargo hold in spaced relations to be substantially in planar alignment with the top of the deck of each lighter; a lighter - ship stabilizing system comprising a wedge block carried by the walkway and lying between the lighter and walkway, said wedge block having a tapered guide slot in the front face thereof, and a tapered wedge adapted to be received in the tapered guide slot to bear against the wedge block on one side and the lighter on the other side to lock the column of lighters against lateral shifting of the lighters relative to the ship when the ship is underway and subject to dynamical conditions.
